CLAIM

The ornamental design for a grater, substantially as shown and described.

DESCRIPTION

FIG. 1 is a top perspective view of a grater showing my new design;

FIG. 2 is a bottom plan view thereof;

FIG. 3 is an end elevational view thereof;

FIG. 4 is a side elevational view thereof;

FIG. 5 is an opposite end elevational view thereof; and

FIG. 6 is a cross sectional view thereof taken along line

6—6 of FIG. 2.

The dominant features of the grater design resides in

the overall configuration of the grater body.
